Application May 31, 1946, Serial No. 673,475

3 Claims. (Cl. 211—89)

1

This invention relates to resilient clamping means and to devices provided therewith.

One object of the invention is the provision of resilient clamping means in which the resilient element is of such character that it is useful to great advantage as a resilient clamping member.

Another object is to provide resilient clamping means comprising a resilient clamping member which is well adapted for direct resilient clamping action on the object to be held by the clamping means.

Another object is the provision of resilient clamping means which is well adapted for holding garments and other articles of varying thicknesses in different portions thereof.

A further object is the provision of a support or hanger which is particularly well adapted for use as a garment hanger.

A yet further object of the invention is the provision of a support or hanger which is of simple and inexpensive construction and which is highly effective, and which although of comparatively small size can be used for holding a large number of garments or other articles.

The above and other objects, features and advantages of my invention will be fully understood from the following description considered in connection with the accompanying drawings which are to be understood as being illustrative of the invention but not in limitation thereof.

In the drawings:

Fig. 1 is a top view of a hanger embodying the present invention;

Fig. 2 is a side view thereof;

Fig. 3 is an end view thereof;

Fig. 4 is a top view of another form of a hanger embodying this invention;

Figs. 5, 6 and 7 are views similar to Fig. 1, showing parts of hangers of other forms, respectively, of the present invention;

Fig. 8 is a perspective view of a paper clamp embodying the present invention;

Fig. 9 is an end view of a paper clamp similar to that shown in Fig. 8 but provided with means for hanging the same in position;

Fig. 10 is a front view of a hanger which is well adapted for use as a skirt or trousers hanger;

Fig. 11 is an end view of the hanger shown in Fig. 10;

Fig. 12 is a side view of a clothes pin embodying the clamping means of the present invention.

As will hereinafter more fully appear the resilient clamping means of the present invention is highly useful in numerous different devices designed for various purposes. Several of such

2

devices will be described but it will be understood that the invention may be applied to numerous other devices and that the invention is not limited in its application to the devices hereinafter specifically described or illustrated in the accompanying drawings.

Referring now to the drawings in detail and first to the embodiment of the invention in a clothes hanger, there is shown in Figs. 1 to 3 a hanger or support 10 intended primarily for use in supporting such articles as skirts, trousers, dresses, etc. although it will be understood that the hangers or supports embodying the present invention may be used for supporting various articles which are not necessarily garments or other articles of wearing apparel. The hanger or support 10 comprises a bracket 12 which as here shown is L-shaped and comprises the parts 14 and 16. Bracket 12 may be attached in any suitable way to a closet wall or other support and for that purpose part 14 of said bracket may be provided as here shown with openings 18 for screws or other fastening means.

In the preferred form of the invention the hanger or support 10 is made of metal and is in the form of a rack, said hanger comprises the outer members 20 and 22 and a plurality of intermediately positioned members 24 which are disposed between said end members 20 and 22. All of said members 20 and 24 are in spaced confronting relation and each pair forms cooperating members defining a space therebetween, as indicated at 26 for the garments or other articles which are mounted on the support and are disposed in said spaces, respectively. Said spaces have open ends as indicated at 28 for the insertion and removal of the articles, said open ends being defined by the adjacent ends of the space-defining members 20 to 24. The opposite ends of said members are secured to the bracket 12 which constitutes the supporting means for said members. The end members 20 and 22 of the rack are provided with stiffening flanges 30 and 32, respectively, and with bent end portions 34 and 36, respectively, said last mentioned end portions as well as the adjacent end portions of flanges 30 and 32 are fastened to parts 14 and 16, respectively, of bracket 12 in any suitable way as by rivets 38. The intermediate spaced members 24 are preferably in the form of flat bars and have bent portions 40 which are riveted or otherwise suitably secured to part 16 of bracket 12 as indicated at 42.

Resilient means comprising resilient clamping members 44 are positioned in the spaces 26 for

resiliently engaging and holding the articles which are inserted in said spaces through the open ends 28 thereof. Said resilient means comprises, in the form of the invention illustrated in Fig. 1, a plurality of thin flat strips of spring steel each strip being in arched form and secured at its opposite ends, in that form, at points spaced longitudinally of the respective members 20 to 24 in any suitable way as by rivets 46. If desired each spring strip 44 may be enclosed within a covering of fabric (not shown). As illustrated, there are two arched spring members 44 in each space 26, the adjacent ends of the two spring members being secured to a companion one of the members 20 to 24 by one of the rivets 46. It will be understood, however, that there need be only one spring member in each space and similarly there may be more than two spring members arranged in end to end relation longitudinally of the companion space-defining members.

Each spring member 44 is highly flexible in a direction transversely of its length and is readily yieldable for flexing movement toward and away from the companion space-defining members to facilitate the insertion and removal of the articles in the spaces in which said spring members are positioned. In this connection, it will be noted further that the spring members 44 extend in curved fashion from the open end 28 of the companion space 26 toward the opposite end of said space and also from the space-defining member to which the spring member is secured toward the companion space-defining member. It will be understood that each spring member is secured only to one of the pair of space-defining members, and it will be noted that each spring member is, in the bowed portion thereof, variably flexible toward and away from the companion space-defining members to compensate for variations in thickness of the garments or other articles which are positioned in the space. The spring members 44 are arranged so that they normally resiliently engage that member of the pair of space-defining members to which the spring member is not secured, and it will be noted that a substantial longitudinally extending bowed portion of each spring member is normally engaged with the adjacent space defining member to which the spring member is not secured whereby a substantial length of the spring member is effective to resiliently engage the article held thereby against said space-defining member.

Since the spring members 44 are variably flexible in different longitudinal portions thereof, progressively along the length of the spring member, in proportion to the flexing force exerted on said portions of the spring member, during the insertion of the article in or removal of the article from the space, each spring member is capable of assuming a variable contour or longitudinal curvature, along its length, to grip or release adjacent portions of the article which in said portions may be of different thicknesses, respectively. Accordingly, each spring member may have one portion thereof flexed further toward the space-defining member to which the spring member is secured than an adjacent portion of said spring member, depending upon the thicknesses of the article at the corresponding portions of the spring member so that the article is resiliently engaged by a substantial length of the spring member.

The spring members 44, in respect to their

resiliency characteristic, may be described by the term "soft," which is a term understood by those skilled in the art as applicable to each spring member 44 which, as described above, can be variably flexed in different or longitudinally successive or spaced portions, respectively, of the flexible bowed part which is made up of these variably flexible portions. By way of illustration it may be stated that spring 44 has a thickness of about .008", but the invention is not narrowly limited to springs of this thickness. As these spring members are made of thin and flexible spring steel and are provided with the above described bowed portions the variable and "soft" flexing characteristic is provided in the bowed portion. Preferably, each spring is pre-formed with the opposite end portions in angular relation to the intermediate longitudinal part of the spring which extends between said end portions so that when the spring is bowed in said intermediate part and said end portions are secured to the companion space-defining member, said end portions lie flat against said space-defining member. Preferably, each spring is dimensioned and arranged and the distance between the confronting surfaces of the companion space-defining members are such that when the spring is arched and is secured at its opposite ends to the space-defining member, the arch is flattened by its engagement with the companion-space-defining member so that a substantial length of the curved or bowed part of the spring normally resilient engages a substantial part of said last mentioned space-defining member when the article is not in place therebetween.

As illustrated in Fig. 4 the space-defining members 50 are secured intermediate the length thereof to a supporting member 52 which may be of any suitable form whereby the spaces between each pair of said members 50 have open ends 54 at the two outer ends thereof. Members 50 are preferably in the form of flat bars and may be secured at their intermediate portions to supporting member 52 in any suitable way as by riveting said intermediate portions to angle irons 56 as indicated at 58. The spring members 44 are secured to one of the companion space-defining members at opposite sides, respectively, of the supporting member 52. The spring members 44 in this form of the invention are thus related to the space-defining members 50 in the same way as described above with reference to Fig. 1 and have the same flexibility and article gripping characteristics hereinbefore described with reference to Fig. 1. In other words the spring members 44 have the same action in both forms of the invention.

The hangers or supports of the present invention are preferably mounted for use in such position that the companion space-defining members, being horizontal, have their confronting surfaces in vertical planes so that the trousers, skirts, dresses, or other articles, which are gripped between the springs and the space-defining members depend therefrom and are suspended from the hanger or support so as to hang down vertically therefrom. It will be noted that the part 16 of the bracket or support 12 provides an effective shelf-like support for the space-defining members; said part 16 being in a horizontal position with said space-defining members thereabove when said bracket is fastened to a wall or other support for the hanger. It will be understood, however, that it is within the scope of this invention to mount the hanger with the bracket

12 in vertical position, if so desired, the confronting surfaces of the companion space-defining members being correspondingly in horizontal position, although the first mentioned position is preferred for in the latter the garments or other articles hang straight down from the hanger and are not folded over the springs or over the space-defining members. The brackets 12 and 52 may be secured in fixed position, as illustrated, or they may be hingedly secured in position so that the hangers can be moved to lie close to the closet wall or to a folded or retracted position when not in use.

As shown in Figs. 8 to 12, the clamping means of the present invention may be embodied in several various ways additional to those illustrated in Figs. 1 to 7 described above. Fig. 8 shows a paper holder 50 which may be used on a desk or table. Said paper holder comprises a base 52 which may be formed of wood, metal, plastic or any other suitable material, and a member 54 formed of any suitable material and forming a cooperating member with base 52 to define a space therebetween and said member having attached thereto a spring 44 of the same character as the springs 44 in the devices shown in Figs. 1 to 7, the opposite ends of said spring being secured to member 54 in any suitable way as by rivets. Member 54 is substantially stiffer than spring 44 and if desired may be substantially rigid so that the spring 44 is the sole resilient clamping member of the device. However, it is within the scope of this invention to make member 54 sufficiently flexible to impart a spring action thereto. As shown in Fig. 8, member 54 is secured at one end thereof to base 52 in any suitable way as by rivets 56 passing through base 52 and an underlapping end portion 58 of member 54. Fig. 9 shows the paper holder provided with an extension 60 of the base 52 so that said holder may be suspended vertically from a suitable support. For this purpose extension 60 is provided with a hole 62 for a supporting nail or hook. The parts of the paper clamp on holder 50A illustrated in Fig. 9 which are the same as the parts of paper holder 50 are designated by the same numerals as in Fig. 8 and it will be understood that member 54' is substantially the same as member 54 except that member 54' has an end portion 58 which is fastened to the front of member 52 by rivets 56.

In Figs. 10 and 11, the invention is shown embodied in a skirt or trousers hanger 70. Said hanger comprises a plate 72 and a plurality of laterally spaced springs 44 fastened at their opposite ends, respectively, to said plate. Said springs 44 bear against companion comparatively rigid members 74, respectively, which are fastened to plate 72 in any suitable way as by brackets 76. One of said brackets is provided with a hook 78 for suspending the hanger from a suitable support. It will be understood that springs 44 have the same characteristics and act in the same way as these springs in the other above described forms of the invention. Members 72 and 74 can be formed of any suitable material and are preferably substantially rigid. It will be understood that the skirt, trousers or other garments or articles may be resiliently clamped between springs 44 and members 74 and thus suspended in vertical position. Instead of connecting the ends of the spring to plate 72, said springs can be connected at their ends to members 74, respectively, and positioned so as to bear on plate 72 in which case the garments or other

articles would be clamped between said springs and the confronting surface of plate 72.

Fig. 12 shows the application of the invention to a clothes pin or the like. The clothes pin so comprises a U-shaped member 82 formed of wood, metal (preferably aluminum), plastic, or of any other suitable material. A spring 44 is connected at its opposite ends in any suitable way as by rivets 46 to one leg 84 of member 82 and bears resiliently against the other leg 86 of said member. It will be understood that clothes pin 82 can be of about the same size and can be used in the same way as the conventional wooden clothes pin except that the clothes are clamped resiliently between spring 44 and the confronting surface of leg 86 instead of between the two legs as in the common wooden clothes pin or the like.

Although I have shown and described the invention embodied in several different devices, the latter are not exhaustive of the uses to which the invention may be put but are intended to illustrate the general application of the resilient clamping means of the present invention.

It will be understood that the hangers or other devices of the present invention may be made of a suitable material or of different materials in different parts of the hangers or other devices. For example, the hangers or other devices may be made of wood or of any suitable plastic. Further, it will be understood that while the springs are hereinbefore described as made of spring steel, they may be made of any suitable material including non-metallic resilient materials.

Thus, it is seen that the resilient clamping means and devices, hangers or supports embodying the present invention are well adapted to accomplish the several objects thereof. It will be understood, however, that various changes in the details of construction and in the arrangement of parts may be made and also that the forms of devices in which the principles of the present invention are utilized may be varied without departing from the underlying idea of the invention within the scope of the appended claims.

Having thus described my invention, what I claim and desire to secure by Letters Patent is:

1. A device for resiliently clamping articles or objects, comprising cooperating members having parts disposed in spaced confronting relation and with adjacent ends of said members at one end of the latter spaced from each other to provide an end-opening to the space between said parts, said adjacent ends being free of mutual displacement and said opening being of constant width, said members being rigidly fixed to each other at their other ends, and a strip of resilient material secured adjacent each end thereof to said part of one of said members at points spaced longitudinally of said one member, said resilient strip being in longitudinally curved form in the space between said two points and extending, in said curved form, longitudinally of said parts of said companion members between said points of securement and projecting from said one of the parts toward the other of said parts in position to resiliently engage and hold an article inserted into said space through said end-opening, the longitudinally curved portion of said resilient strip between said longitudinally spaced points of securement being flexibly movable along its length in a direction transversely of the space between said parts to permit the insertion of the article through said end-opening to a position 75 between said resilient strip and the adjacent

confronting portion of said part of the companion space-defining member while said members are held rigidly together at said other ends thereof.

2. A hanger for garments or other articles, comprising longitudinal cooperating members disposed in spaced confronting relation and defining a space having an opening at the adjacent outer ends of said members for the insertion and removal of the article in and from the space between said members, said outer ends being free of mutual lateral displacement and said opening being of fixed extent, means rigidly securing said members together at the adjacent ends thereof opposite their said outer ends, and a resilient strip highly flexible in a direction transversely of its length secured adjacent each end thereof at longitudinally spaced points on one of said members in position in said space, said resilient strip being formed of flat stock and having a bowed portion extending longitudinally of said space and being flexibly movable in said space, variably in adjacent longitudinal portions of the strip between said points of securement thereof, toward and away from said members and arranged to permit the article inserted in said space and to be positioned between said strip and a confronting part of one of said members while said members are in said rigidly held relation and to be resiliently held by the strip against said confronting part, said space-defining members being sufficiently rigid transversely of their lengths to prevent substantial downward flexing thereof, under the weight of the garments or other articles supported by the hanger.

3. A hanger for garments or other articles comprising at least three rigid longitudinal members disposed in spaced parallel relation and one of said members being located between and confronting the other two of said three members, de-

fining spaces therebetween, a rigid bracket secured to said three members at their adjacent inner ends, the outer ends of said members being free and defining end-entrance openings to said spaces between said members, respectively, said bracket holding said members rigidly in said spaced relation and providing means for supporting said hanger, and resilient strips secured in the spaces between said members and extending longitudinally thereof, each strip being highly flexible transversely of its length, each of said strips being secured at its opposite ends to one of said members and having an intermediate bowed portion projecting toward the companion confronting member, each of said bowed portions being variably flexible along its length and readily yieldable along its length in engagement with the garment or other article as the latter is inserted through the companion one of said end-entrance openings longitudinally of the companion space-defining members.
